UNITED STATES PATENT OFFICE.

EDGAR W. HELLER, OF NEWARK, NEW JERSEY.

FILTER-PRESS.

942,173.

Specification of Letters Patent.

Patented Dec. 7, 1909.

Application filed February 11, 1909. Serial No. 477,379.

To all whom it may concern:

Be it known that I, EDGAR W. HELLER, a citizen of the United States, residing at Newark, county of Essex, and State of New Jersey, have invented certain new and useful Improvements in Filter-Presses, of which the following is a specification, reference being had therein to the accompanying drawings, in which—

- 10 Figure 1 is a side elevation of a filter press, a portion of the operating mechanism being shown in vertical sectional view; Fig. 2 a plan view, a portion of one of the heads being broken away to show one of the compression rams; Fig. 3 a vertical sectional view showing a compression ram connected directly to the jack screw; and Fig. 4 a similar view showing another arrangement of ram directly connected to the jack screw.
- 15 Heretofore ordinary jack screws have been used to force the filter plates together and to hold them against the pressure of the liquid pumped in between them. This form of press, while simple in construction and readily and quickly operable, is unsatisfactory in that it is difficult and very laborious to secure the proper pressure on the filter plates. In the hydraulic filter presses wherein a hydraulic ram is used to force the filter plates together the construction is complicated, and the operation is slow and tedious, particularly the operation of releasing and withdrawing the ram to permit of the separation of the plates and the shifting head.
- 20 It is one of the main objects of this invention to combine the jack screw system with the hydraulic system to secure the advantages of both systems. By my invention I secure a rapid adjustment of the shifting head and filter plates by means of the jack screws and an adequate pressure on the plates by means of the hydraulic ram.
- 25 Another object of the invention is to so arrange the hydraulic compression apparatus that it will not interfere with the operation of the jack screw for the purpose of adjusting the shifting head to the filter plates.
- 30 Another object of the invention is to provide means whereby the thrust of the jack screw will be taken up directly by the compression head and the compression rams thereby relieved.
- 35 Other important objects and advantages of the invention will appear hereinafter.

Referring to the various parts by numbers, 1 designates the filter plates; 2 the rear support or stationary head; 3 the shifting head; 4 the horizontal supporting bars on which the filter plates and the shifting head are mounted. These bars connect together the stationary head and the compression head 5. 6 designates suitable supports for the stationary compression plate 2 and the compression head 5. These parts of the apparatus may be of any desirable form, that shown in the drawings being merely by way of illustration.

Extending horizontally and longitudinally through the compression head is a jack screw 7 which, at its inner end, engages the projection 8 of the shifting head and on its outer end carries the large hand wheel 9. This jack screw extends through an opening 10 in the compression head so that it may be moved freely through said head without rotation therein. Threaded on the jack screw near the inner side of the compression head is a horizontal cross-head 11. Also threaded on the jack screw between said cross-head and the compression head is a thrust block and lock nut 12. Journalized in suitable bearings on the upper side of the compression head is a short shaft 13 carrying at its inner end a small gear 14 which meshes with a gear 15 formed on the periphery of the thrust block 12. On the outer end of the shaft 13 is secured a hand wheel 16. It is obvious that by rotating the shaft 13 the thrust block and lock nut will be rotated on the jack screw. The said thrust block is considerably wider than the gear 14 so that said thrust block may have a longitudinal movement on the jack screw and also with it without becoming disengaged from the gear 14.

In the compression head, on each side of the jack screw, are mounted two hydraulic rams 17 whose operating ends are adapted to engage the cross-head 11, as shown clearly in Fig. 2. These rams are supplied with fluid by a pump 18 through pipes 19, said pump being operated by means of a handle 20. It will, of course, be understood that any form of pump may be employed and that said pump may be hand-operated or not as desired.

In order to prevent the ram plungers from being forced out of their cylinders I provide a means for arresting and preventing the operation of the pump when said plun-

gers have reached a predetermined position in their forward travel. This means consists of an angle lever 21 pivoted on a cross-bar 22 carried by the side bars 4 of the 5 press frame. The lever 21 is provided with a sleeve 23, the arms of the lever being secured to opposite ends of said sleeve. One arm of said lever is connected by a link 24 to a stop lever 25, one end of which is 10 adapted to be swung into the path of the handle 20 of the pump when the rams have reached the limit of their outward movement. The upper end of one arm of the lever 21 is in the path of the cross head 11, 15 as shown clearly in Fig. 1, and is so positioned that when said cross-head has been moved outwardly by the rams to a predetermined point said lever arms will be engaged by the cross-head and the stop arm 25 20 swung downward to the pump handle. It will thus be seen that the accidental withdrawal of the ram plungers from their cylinders will be prevented.

It is, of course, obvious, that any suitable 25 arrangement of levers and stop bar may be provided, it being only necessary that the cross head engage some form of pump-stopping means.

In Fig. 3 the jack screw is directly connected to a ram 17^a which is threaded on 30 said screw. This ram is provided on its exterior with a lock nut 21 which is adapted to be turned back against the compression head to relieve the ram of the thrust on the 35 jack screw. The ram is formed with an outwardly extending guiding part 22 which fits a corresponding aperture in the compression head; and the ram proper and the guiding part are provided with packings 23 40 to prevent the escape of the pressure fluid, said fluid being delivered through pipe 24.

In the construction illustrated in Fig. 4 45 the ram 17^b is threaded directly on the jack screw and is provided with a lock nut and thrust block 25. The ram is formed with an internal recess or chamber 26 into which projects a tubular guiding part 27 formed integral with the compression head. Packings 28 are provided to prevent the escape 50 of the compression fluid, which fluid is supplied through pipe 29.

In the operation of the apparatus the filter plates are brought together in the usual manner and the jack screw is rotated 55 to bring the shifting head against said plates. The screw is operated by means of the hand wheel 9 to bring the filter plates and the shifting head into close contact. It is not intended that any considerable pressure 60 shall be applied by means of the jack screw, said screw being used for the purpose of rapidly bringing the shifting head into position and for bringing the filter plates and said heads into close contact.

65 When the shifting head has been properly

positioned by means of the jack screw the required pressure is pumped into the rams, the operating ends of the rams engaging the cross-head 11 and forcing the jack screw forward to bring the desired pressure on the 70 shifting head. When this pressure is secured the thrust block 12 is rotated by means of the gear 14 and hand wheel 16 to shift said thrust block back against the compression head, thus locking the screw jack and 75 relieving the rams of the thrust of the shifting head. It will thus be seen that I combine the convenience of the rapidly moving jack screw for bringing the shifting head and the filter plates into close contact with 80 the efficiency of the hydraulic ram for securing the desired pressure on the shifting head and the plates. When it is desired to open the press the rams are again operated to force forward the cross head and the jack 85 screw and thereby relieve the thrust block and lock nut of the thrust of the shifting head. The thrust block is then run out on the jack screw by means of the hand wheel 16 and the gear 14. When the thrust block 90 is thus freed from the compression head the pressure in the rams is released and then the jack screw is operated to release the shifting head.

From the foregoing it is manifest that I 95 provide a simple and efficient means for securing the desired pressure on the shifting head and the filter plates which combines the advantages of the old jack screw type of press and the hydraulic type, and eliminates the disadvantages of both of said types of presses.

Having thus described my invention what I claim as new and desire to secure by Letters Patent is:—

1. A filter press comprising a shifting head, filter plates, means for rapidly adjusting the shifting head to said plates, a hydraulic means for applying the final pressure to said shifting head, and means whereby the adjusting means may be locked against movement to relieve the hydraulic means of the thrust of the shifting head.

2. A filter press comprising a shifting head, filter plates, a jack screw for rapidly adjusting the shifting head to said plates, a hydraulic means for applying the final pressure to said shifting head, and means adapted to engage the jack screw to relieve the hydraulic means of the thrust of the shifting head.

3. A press comprising a shifting head, means for rapidly adjusting the shifting head, a hydraulic means for applying the final pressure to said shifting head, and means whereby the adjusting means may be locked against movement to relieve the hydraulic means of the thrust of the shifting head.

4. A press comprising a shifting head, a

jack screw, means for rotating the jack screw for rapidly adjusting the shifting head, means for moving said jack screw longitudinally without rotation to apply the final pressure to the shifting head, and means adapted to engage the jack screw to relieve the hydraulic means of the thrust of the shifting head.

5. A filter press comprising a shifting head, filter plates, a jack screw for rapidly adjusting the shifting head, means for moving said jack screw longitudinally without rotating it to apply the final pressure to the shifting head, and means to lock said screw to take up the thrust of the shifting head.

6. A filter press comprising a shifting head, filter plates, a jack screw for rapidly adjusting the shifting head, hydraulic means for moving said jack screw longitudinally without rotating it, and means to lock said screw and to take the thrust of the shifting head from the hydraulic means.

7. A filter press comprising a shifting head, filter plates, a compression head, a jack screw running through said head and adapted to rapidly adjust the shifting head, hydraulic means mounted in the compression head and adapted to move the jack screw longitudinally without rotating it, and a lock nut and thrust block adapted to be brought to bear against the compression head to relieve the hydraulic means of the thrust of the shifting head.

8. A filter press comprising a shifting head, filter plates, a compression head, a jack screw running through said head and adapted to rapidly adjust the shifting head, a hydraulic ram mounted in the compression head and adapted to move the jack screw without rotating it, a thrust block on the jack screw and adapted to be brought to bear against the compression head, and means for rotating said thrust block.

9. A filter press comprising a shifting head, filter plates, a compression head, a jack screw running through said head and adapted to rapidly adjust the shifting head, a cross-head on the jack screw, a pair of rams mounted in the compression head and adapted to engage the cross head to move the jack screw longitudinally without rotating it, a lock nut and thrust block on the jack screw and adapted to be brought to bear against the compression head to relieve the rams of the thrust of the shifting head.

10. A filter press comprising a shifting head, filter plates, a jack screw for rapidly adjusting said head and plates, a ram for moving the jack screw to bring the final pressure on the shifting head, a pump to operate said ram, and means operated by the ram to stop the pump when the rams have moved a predetermined distance.

11. A filter press comprising a shifting head, filter plates, a compression head, a

jack screw running through said head and adapted to rapidly adjust the shifting head, a cross-head on the jack screw, a pair of rams mounted in the compression head and adapted to engage the cross head to move the jack screw longitudinally without rotating it, a lock nut and thrust block on the jack screw and adapted to be brought to bear against the compression head to relieve the rams of the thrust of the shifting head, and means operated by the cross-head to prevent the operation of the rams after they have moved a predetermined distance.

12. A filter press comprising a shifting head, filter plates, means for rapidly adjusting the shifting head, a ram for applying final pressure to the shifting head, and means operated by the ram plunger after it has moved a predetermined distance to stop the operation of the ram to thereby prevent further movement of the ram plunger.

13. A filter press comprising a main frame, filter plates mounted therein, a shifting head adapted to move in said frame and to bear against the said filter plate, a jack screw supported in the frame, its free end adapted to bear against the shifting head, rotatable means for rapidly adjusting said jack screw to bring its inner end to bear on the shifting head, hydraulic means adapted to move said jack screw longitudinally without rotation to apply the final pressure to the shifting head, and means for locking the jack screw to relieve the hydraulic means of the thrust of the shifting head.

14. A filter press comprising a shifting head, filter plates, a jack screw for rapidly adjusting the shifting head to said plates, and a hydraulic means on diametrically opposite sides of the jack screw and between the ends thereof to move said jack screw longitudinally without rotation to apply the final pressure to the shifting head.

15. A filter press comprising a shifting head, filter plates, a jack screw for rapidly adjusting the shifting head to said plates, and means on diametrically opposite sides of the jack screw and between the ends thereof to move said jack screw longitudinally without rotation to apply the final pressure to the shifting head.

16. A filter press comprising a shifting head, filter plates, a jack screw for rapidly adjusting the shifting head to said plates, and means adapted to engage the screw at a point between its ends to move said screw longitudinally without rotation to apply the final pressure to the shifting head, and means to engage the jack screw to take up the thrust of the shifting head.

17. A filter press comprising a shifting head, filter plates, a jack screw for rapidly adjusting the shifting head to said plates, and hydraulic means adapted to engage the

screw at a point between its ends to move
said screw longitudinally without rotation
to apply the final pressure to the shifting
head, and means to engage the jack screw
5 and relieve the hydraulic means of the
thrust of the shifting head.

In testimony whereof I hereunto affix my

signature in the presence of two witnesses
this first day of February 1909.
